(57) CLAIM

The ornamental design for a fruit bowl with banana holder, as shown and described.

DESCRIPTION

FIG. 1 is a top, front, left perspective view of a fruit bowl with banana holder showing our new design;

FIG. 2 is a rear elevation view thereof;

FIG. 3 is a front elevation view thereof;

FIG. 4 is a left side elevation view thereof, a right side elevation view being a mirror image of the left side elevation view;

FIG. 5 is a top plan view thereof; and,

FIG. 6 is a bottom plan view thereof.

The broken lines in the drawings represent portions of the fruit bowl with banana holder that form no part of the claimed design.

1 Claim, 4 Drawing Sheets
